(57) **CLAIM**

The ornamental design for a disposable endcap display case, as shown and described.

DESCRIPTION

FIG. 1 is an isometric view of my new design for a transparent disposable endcap display case;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a perspective view thereof, with some shelves shown in an alternate position of use, and displaying compact fluorescent lamps.

The broken line display of the compact fluorescent lamps is for illustrative purposes only and forms no part of the claimed design.
